(57) **CLAIM**

The ornamental design for an eyewear module, as shown and described.

DESCRIPTION

FIG. 1 is a perspective view of the eyewear module of the present invention;

FIG. 2 is an alternate perspective view of the eyewear module thereof;

FIG. 3 is a top plan view thereof;

FIG. 4 is a front elevational view thereof;

FIG. 5 is a lateral elevational view thereof;

FIG. 6 is a bottom plan view thereof; and,

FIG. 7 is a medial perspective view thereof from the bottom. Phantom lining, where utilized, is for illustrative purposes only and is not intended to limit the claimed design to the features shown in phantom.
